PORTABLE GEAR CASE CLEANER

Filed March 17, 1934

UNITED STATES PATENT OFFICE

2,001,302

PORTABLE GEAR CASE CLEANER

James K. Delano, New York, N. Y.

Application March 17, 1934, Serial No. 716,041

4 Claims. (Cl. 184—1.5)

This invention relates to a portable apparatus for cleaning and removing the old lubricant from gear casings of automobiles or other places where gearing is run in an oil or grease bath, and where 5 it is desired to change the lubricant from time to time.

In the removal of old lubricant from the gear casing of automobiles and the cleaning of the same preparatory to being refilled, it is in many 10 cases the practice to place the automobile over a pit or upon a raised lift, and to place under the drain hole of the gear casing, a drain pan or funnel that is mounted upon a swinging pipe arm that is secured to the side of the pit and 15 which leads to a container for the old lubricant, but while such a drain pan may be located under the drain hole of the gear casing, it cannot be raised or lowered to accommodate the difference in height of different automobiles between the 20 hole in the gear casing and the ground level and the position of the drain funnel and pan.

While it is important that the drain pan be placed in close proximity to the drain hole in the gear casing so that the lubricant being 25 drained out will enter the drain pan and not spill over the sides, etc., it has been found that with the present method of injecting compressed air or even a cleaning fluid into the gear casing through the drain hole which has to be done by 30 introducing a service hose into the drain hole, that this method requires that the drain pan be spaced far enough away from the drain hole to allow of the service hose being introduced between the gear casing and the edge of the drip 35 pan, which will allow of drip and slop of the lubricant.

The object of the present invention is to provide a portable cleaning apparatus that may be mounted in an adjustable relation with the gear 40 casing of a vehicle.

Another object of the invention being to provide means whereby the apparatus may be mounted in close proximity to the drain hole of the gear casing, and the injecting and draining 45 means both contained within the apparatus.

Another object is to provide means whereby the air that is injected into the gear casing is heated during its passage through the apparatus.

Another object being to heat the old lubricant 50 as it is drained through the apparatus, to cause it to partly liquefy, and not to clog in the drainage passage of the apparatus.

With these and other objects in view, my invention consists in certain novel construction 55 and combination of parts as will hereinafter be

fully described and claimed and also illustrated in the accompanying drawing which forms a part hereof and in which like figures of reference refer to corresponding parts in all of the views, and it is understood that slight changes may be made without departing from the spirit of the invention. 5

In the drawing:

Figure 1 shows a front elevation of the apparatus, partly in section and showing the same as 10 attached to the drip pan of a drain pipe mounted in a greasing pit, over which the automobile is placed.

Figure 2 shows a cross section of the same, taken on the line 2—2 of Figure 1. 15

Figure 3 is a cross sectional view taken on the line 3—3 of Figure 1.

Figure 4 shows a view of another form of nozzle member that may be interchanged with other 20 styles of nozzle members.

Figure 5 shows another type of nozzle member in which several sections are pivoted together and which may be swung into different directions. 25

Referring to the drawing:

In Figure 1 I have indicated by the numeral 25 10 the usual drain pan that is mounted upon the swinging drain pipe 12 which is attached to the side of the greasing pit, and which may be swung under the gear casing of the automobile to catch the old lubricant as the same drains out 30 through the drain hole in the gear casing after the plug has been removed.

The apparatus as herewith shown, comprises a tubular inverted cone-shaped cap 13 which is formed with a depending flange 14 which rests 35 upon the upper edge of the drain pan 10, or upon the upper edge of any drainage funnel, and is detachably secured thereon by the clamps 15 operated by the eccentric hand-levers 16, or other suitable means of attachment. 40

The upper part of the cap 13 is formed with a neck having a flange 17 for attachment by the bolts 18 to a flange 19 which is formed on the bottom of the tubular member 20 which is also formed with a neck 21 telescoping into the lower 45 part 22 of the drain funnel 23 and retained in place by the locking device 24 in such a manner that the funnel 23 may be raised or lowered to bring it into proper operative position with respect to the drain hole of the gear casing. 50

The body portion of the tubular member 20 is provided with a concentric heating chamber 25 which is spaced from the sides of the body member 20 by a spider 26 and which is also formed with a dome 27 having a flanged central 55

opening 21 within which is secured the lower end of the injection pipe 28; said pipe 28 being supplied with the coupling 29 for the threaded nipple 30 to which is detachably secured any one of several different styles and types of nozzle members 31, having the nozzle ends 32.

The lower end of the heating chamber 25 is provided with a base of insulating material 33 within which is molded or otherwise secured a 10 socket 34 for the heating element 35 of the usual type which is threaded therein and supplied with electrical current by the wires 36 from the supply cable 37, one end of which is mounted in said base 33 and lead out through the side of the cap 15 13 and the boss 38, having a plug connection 39.

The insulation base block 33 is also provided with a pipe 41 through which air is fed to the heating chamber 25 by the air feed pipe 42 from some suitable air pressure device; the air supply 20 pipe 42 being detachably secured to the air feed pipe 41 by the coupling 43.

The upper end of the air feed pipe 41 is formed with a ball valve having the ball 45 which is in contact with a thermo-metal plate 46 attached to 25 the base 33 by the screws 47 in such a manner that as this plate 46 becomes heated its free end will curve upward and lessen its pressure upon the ball 45 and admit more air to the heating chamber 25.

30 For retarding the passage of the heated air through the heating chamber 25, I have provided the inner walls of the chamber 25 with a spiral deflector 48 which is spaced from the heating element 35 in such a manner that the air entering through the pipe 41 and ball valve 45 will have to follow the spiral upward, thus being retained longer in the chamber 25 to become heated to a greater degree than if allowed to pass freely upward.

40 The neck 22 of the body member 20 receives the old lubricant from the funnel 23 and conveys it down through the space between the body member 28 and the heating chamber 25 to the drain pan 10; it being heated and liquefied as it passes 45 down by the side of the heating chamber 25.

The nozzle member 50 shown in Figure 4 is flexible to accommodate a side opening in a gear casing and other places where a straight nozzle member will not readily enter.

50 The form of nozzle member shown in Figure 5 comprises several tubular arms 52 which are hinged together as at 53, and to a member 52 which is adjustably mounted within a member 51 that may be substituted for any of the other 55 forms of nozzle members.

In the operation of the device, the funnel 23 having been placed under the drain hole of the gear casing, and raised into position whereby the nozzle 32 enters through said drain hole; and current having been applied to the heater element 35 to heat the chamber 25.

Air is then admitted through the feed pipe 42 and the pipe 41, entering the chamber 25 through the ball valve; the quantity of air admitted and 65 the rate of admission being governed by the thermostat; the air passing upward and following the spiral 48 to the dome 11, and from there up through the injection pipe 28 and through the nozzle member and nozzle into the gear casing, 70 the amount of air passing through the valve being due to the further opening of the same as the thermostat becomes heated.

The old lubricant from the gear casing will

drain downward through the funnel 23, the neck 21 and the passage formed by the body 20 and the heating chamber 25, past the spider legs 26 and into the drain hopper 10.

Having thus described my invention, what I 5 claim as new and desire to secure by Letters Patent, is:

1. In a portable cleaning device for gear casings, the combination with a tubular member having a drainage funnel and an injection device, of a heating chamber formed within said tubular member and communicating with the injection device, a heating means mounted therein and adapted to heat the same, means for feeding air to said heating chamber, means for regulating the rate of such feed, means for retarding the passage of the air through said heating chamber, and means for mounting said cleaning device adjacent to the gear casing. 15

2. In a portable device for cleaning gear casings, the combination with a tubular member, an adjustable funnel mounted on the upper end thereof to receive the drainage from the gear casing, a mounting means attached to the lower end of said tubular member for supporting the 20 same, a heating chamber contained within said tubular member and spaced therefrom, an electrical heating element mounted within said heating chamber for heating the same, a hot air injecting means communicating with said heating chamber and adapted to enter the gear casing, 25 means for passing air through said heating chamber, automatic means for regulating the passage of the air, and means for retarding the passage of the air therethrough. 30

3. In a portable cleaning device for gear casings, the combination with a tubular body having a lubricant receiving end and a discharge end, a heating chamber mounted within said tubular body, an electrically operated heating 40 element for said heating chamber, an injection means communicating with said heating chamber and adapted to enter the gear casing, means for passing air through said heating chamber, means actuated by the temperature of said heating 45 chamber for controlling the volume of air admitted to said chamber, and means for causing the heated air to pass slowly through said heating chamber and assume a spiral path therethrough. 50

4. In a portable cleaning device for gear casings, the combination with a supporting and drainage means, of a tubular base adapted to be detachably secured to the supporting means, a tubular drainage member secured to said base 55 and in adjustable relation to the gear casing, a tubular member concentric with and mounted within said drainage member and having a dome-shaped upper end forming a heating chamber and provided with an injection nozzle for entering into said gear casing, a plug of insulating material for closing the lower end of said heating chamber, an electrical heating element mounted within said heating chamber and detachably within said plug and means for energizing the 60 same, an air supply pipe for feeding air to said heating chamber, a control valve for said feeding pipe and means actuated by the temperature within said heating chamber for operating said valve. 65
